UNITED STATES PATENT OFFICE.

ALBERT UHL, OF ENGLEWOOD, NEW JERSEY.

DESIGN FOR LACE EMBROIDERY PANEL.

Application filed August 27, 1926. Serial No. 18,886. Term of patent 7 years.

To all whom it may concern:

Be it known that I, ALBERT UHL, a citizen of Switzerland, residing at Englewood, in the county of Bergen, in the State of New Jersey, have invented a new, original, and ornamental Design for Lace Embroidery Panel, of which the following is a specification, reference being had to the accompanying drawing, forming part thereof.

The figure of the drawing is a face view, showing my new design.

I claim:

The ornamental design for lace embroidery panel as shown.

ALBERT UHL.
